UNITED STATES PATENT OFFICE.

MARLEY C. MOULTON, OF MAPLEWOOD, MISSOURI, ASSIGNOR TO LAWRENCE M. STEIN,
OF WINNETKA, ILLINOIS.

BLINDSTITCH SEWING MACHINE.

Application filed May 6, 1924. Serial No. 711,359.

This invention relates to improvements in blind stitch sewing machines for felling a superimposed layer upon a base layer of material and the principal object of the invention is to provide a novel mechanism by means of which the line of stitching connecting the base and superimposed layers may be located at a distance remote from the folded edge of the superimposed layer.

In the manufacture of garments, such as, plain edge coats in which the line of stitching along the infolded edge of the coat is omitted, the facing is secured to the outside or body of the coat, or to the stiffening member, by a line of stitching located at a distance remote from the edge of the garment. In the manufacture of such garments heretofore this line of stitching has been made by hand. One of the objects of the present invention is to provide a machine capable of accomplishing this work which has heretofore been done by hand, that is, a machine capable of securing the facing to the body or stiffening member of the coat by a line of blind stitching located at a distance remote from the edge of the coat or other garment.

A further object of the invention is to provide a blind stitch sewing machine in which the layers of a piece of material, which has been folded, may be secured together at such distance from the edge of the fold that the fold may be pressed out to form a plait of any desired width and particularly of sufficient width to be pressed into the form of a box plait.

A further object of the invention is to provide a blind stitch sewing machine with a bender supported upon the bed plate of the machine, so constructed as to engage an up-turned edge of a superimposed layer, or to engage the superimposed layer within a fold and present the up-turned or folded edge of the layer in the path of the needle.

A further object of the invention is to provide a blind stitch sewing machine for felling a superimposed layer upon a base layer which comprises a bed plate, an overhanging arm having a head carrying stitch forming mechanism, feeding mechanism, a presser foot and a yieldable work support extending through the bed plate into co-operative relation with the presser foot to clamp the work therebetween, with bender

mechanism supported upon the bed plate and operable simultaneously with, and preferably by, the work support in such a manner that when the work support is depressed from clamping relation to the presser foot the bender will be simultaneously moved out of operative position in order to facilitate the introduction and removal of the work.

A further object of the invention is to provide a machine of the character above described with a removable work supporting table carrying a bender of the character above described so that the machine may be capable of being used for ordinary felling or padding or may be employed to do the special kinds of work above described.

A further object of the invention is to provide a novel means for supporting the work as it passes from the work supporting table to the yieldable work support which co-operates with the presser foot. This is accomplished by providing a bridge which is pivotally connected at one end to the table and at its other end to the work support.

A further feature of the invention consists in providing a bridge of this character with means which will enable the operator to retard the feed of the base layer in order to prevent wrinkling or checking of the goods where fine material is operated upon and the material advanced by an upper feeding mechanism.

Other objects and features of the invention will more fully appear from the following description and the accompanying drawings and will be particularly pointed out in the claims.

A preferred embodiment of the invention is disclosed herein as associated with a sewing machine of the well known "Arbette" type and more particularly with the sewing machine disclosed in my prior Patents Numbers 1,469,675 and 1,469,676, granted October 2, 1923 respectively for improvements in work presenting mechanism for sewing machines and feeding mechanism for sewing machines. The work table which is illustrated in the accompanying drawings and upon which the bender mechanism is mounted may be and desirably is of the general form disclosed in my prior Patent Number 1,438,255, granted December 12, 1922. It will, however, be understood that the invention

may be associated with, or embodied in, other types of machines than that which is particularly illustrated and described herein.

In the drawings:—

6 Fig. 1 is an end elevation, partly broken away and partly in section, of a sufficient portion of a sewing machine to show the manner in which the present invention is associated therewith;

10 Fig. 2 is a plan view of the work table and bender mechanism and also illustrating in plan the presser foot removed from its support upon the head of the machine;

15 Fig. 3 is a front elevation of the table and bender mechanism mounted upon the bed plate of the sewing machine, the bed plate being shown in section, and also illustrating in elevation the work support, the means for depressing the same, and other parts of 20 the machine located beneath the bed plate;

Fig. 4 is a detail view of the work supporting table and bender mechanism viewed from the right toward the left;

25 Fig. 5 is a detail front elevation of the presser foot and bender mechanism for the superimposed layer, illustrating the manner in which the same is carried by the work supporting table, a portion of which is shown in section;

30 Fig. 6 is an underside plan view of the presser foot, also illustrating in full lines a portion of the bender in operative relation to the guide and presser foot and showing in dotted lines the bender removed from operative position to facilitate the introduction and removal of the work; and,

35 Fig. 7 is a vertical sectional view through the presser foot in a plane parallel to the line of stitching and viewed from the left 40 toward the right.

The sewing machine illustrated in the accompanying drawings comprises a bed plate 1 from which rises an overhanging arm 2 having a head 3 which carries a vibrating 45 and reciprocating preferably curved oscillating needle 4, complementary stitch forming mechanism, such as, a rotary bobbin-containing hook 5, a presser foot 6, a feed dog 7 and means for actuating these various

50 mechanisms which, being well known, need not be described herein. A yielding work support 8 co-operates with the presser foot to clamp the work therebetween and the feed dog 7 also co-operates with the work support 55 in advancing the work in a well known manner. The work support 8 is fixedly secured upon the upper end of a hollow stem 9 which is slidably mounted in a tubular standard 10 which is slidably mounted in a bracket 11 which depends from the under surface of the bed plate 1. The hollow stem 9 is provided with opposite guide slots 12 which receive the cylindrical ends of screws 13 which are seated in the wall of

60 65 the standard 10 and the work support is

normally sustained in elevated position to co-operate with the presser foot 6 by a helical spring 14 which bears at its upper end upon the under wall of the work support and is seated at its lower end upon a support 15 which is secured to the standard 10 by screws 16 and also serves as a guide for the stem 17 of the bender 18 which raises the base layer into the path of the needle.

The tubular standard 10 is normally held 75 in elevated position by a collar 19 which is secured to the standard and is provided with a hollow boss 20 which receives the upper end of a helical spring 21, the lower end of which is seated in a socket in an adjusting screw 22 in the arm 11 of the supporting bracket. The boss 20 is provided with a transverse rib 23 which extends across its top and is engaged by a depressing lever 24 which is pivotally mounted at one end upon a stud 25 upon the depending bracket for the work support. The free end of the lever 24 is engaged by the overlying end of a lever 26 which is secured to a shaft 27 mounted in suitable bosses extending downwardly from the bed plate 1 and the shaft 27 has fixed to it a downwardly extending arm 28 to which is secured an arm 29 adapted to be actuated by the knee of the operator. Thus when the arm 29 is forced laterally (to the right) the lever 26 will be swung downwardly and will depress the lever 24 and thereby, acting through the rib 23 on the collar 20, will depress the tubular standard 10 and remove the work support from work clamping position.

The lower end of the bender stem 17 is secured to a cross head 30 which is reciprocably mounted in the tubular standard 10 and is provided with a transverse slot 31 which receives the rounded end 32 of a bender actuating arm 33 which is oscillated in timed relation to the action of the stitch forming mechanism in a manner well known and which need not be further described.

The particular bender mechanism and other mechanisms above referred to are fully described in the prior patents heretofore mentioned.

In usual types of blind stitch sewing machines of the "Arbette" type the edge of the superimposed layer is guided in parallelism with the path of the needle and adjacent thereto and the base layer is presented in the path of the needle by the lower bender which operates through the work support, while the under face or edge portion of the superimposed layer is presented in the path of the needle either by a guide upon the presser foot or by a bender carried by the presser foot.

One of the objects of the present invention is to provide a novel bender mechanism for the superimposed layer which will bend the layer into one of the paths of reciproca-

tion or oscillation of the vibrating needle. Preferably the presser foot is provided with a guide for the turned-up or folded edge of the superimposed layer which lies adjacent to or crosses one of the paths of oscillation of the needle and co-operates with the bender for the superimposed layer in such a manner as accurately to insure the proper penetration of the needle into the material 10 of the superimposed layer at or beneath the edge thereof.

The preferred form of presser foot which is illustrated in the accompanying drawings comprises a body portion 33 having a forwardly extending toe 34 provided with a lateral extension 35 having guideways 36 and 37 for the oscillating needle and an upwardly extending edge 38 forming a guide for the edge of the superimposed layer which 20 may be directed into contact therewith by the hand of the operator.

The presser foot is provided with a pair of upwardly extending ears 39 and 40 which are secured to the hook bracket which 25 depends from the sewing machine head.

The preferred form of guide which is illustrated herein comprises a member 41 having a bifurcated lower end the arms 42 and 43 of which lie upon opposite sides of 30 the path of the needle 4 as illustrated more particularly in Fig. 7 and the bender is so located as to press the up-turned edge or folded portion of the superimposed layer against this guide intermediate of the arms 35 42 and 43 so that the needle will pass through the edge portion of the superimposed layer at a predetermined depth of penetration.

It will be understood, however, that other forms of guides may be used or that the bender may be employed without a co-operating guide thus to force the edge portion of the superimposed layer into the path of the needle.

One of the objects of the invention is to 45 provide means for supporting the bender from the bed plate of the machine instead of mounting it upon the presser foot in order that the bender mechanism may be readily removed as will hereinafter more fully appear when other work is to be done upon 50 the sewing machine not requiring the presence of this bender. Furthermore, the novel construction is such that other types of bender such as those supported by a presser 55 foot may be readily used upon the machine.

Any suitable means may be provided for supporting the bender from the bed plate of the machine. In the present embodiment of 60 the invention the bender for the superimposed layer is supported upon a work table which is detachably mounted upon the bed plate so that both the work supporting table and bender can be readily removed when desired. The bender supporting mechanism 65 may, however, be directly mounted upon the

bed plate of the machine within the scope of the present invention.

The preferred form of work supporting table which is illustrated herein is substantially the same as that shown in my prior 70 Patent Number 1,438,255 aforesaid and comprises a top 44 which preferably is located in a lower plane than the normal plane of the work support when the latter is in co-operative work clamping relation to the 75 presser foot and is supported upon vertical front and rear walls 45 and 46 which are connected by and continuous with a side wall 47. An integral horizontal extension 48 projects from the lower end of the rear 80 wall 46 and is provided with a downwardly projecting stud 49 having an enlarged head 50 adapted to pass through a key-hole slot in the bed 1 so that when the stem of the stud 49 is moved into the narrow portion 85 of the key-hole slot the stud will anchor the extension 48 to the table. The front wall 45 of the table has a central thickened portion 51 having a vertical slot 52 therein which receives an extension or boss 53 90 forming part of a T-shaped plate 54 the arms of which are secured to the lower ends of the thickened wall 51 by screws 55. An adjusting screw 56, which is threaded through the T-shaped plate 54, is rotatably 95 connected at its inner end to a post 57 which is pivotally mounted upon a screw or stud 58 mounted in parallel flanges 59 the inner walls of which form continuations of the walls of the slot 52 and which serve as 100 guides for preventing lateral movement of the post 57. The lower end of the post is provided with a downwardly extending stud 60 having an enlarged head 61 adapted to pass through an aperture, preferably a 105 key-hole slot 62 in the bed plate, or as illustrated herein in Fig. 3 in a plate 63 which is sunken into and secured to the bed plate.

In order to assemble the table upon the bed plate of the machine the studs 49 and 60 are inserted through the key-hole slots in the table and the screw 56 rotated in a direction to move the lower end of the post 57 toward the stud 49, thus causing the heads 50 and 61 of the studs 49 and 60 to 110 engage the walls of the slots or apertures through which the studs extend and lock the table firmly upon the bed plate.

In order to remove the table from the machine it is merely necessary to unscrew the 115 screw 56 until the heads 50 and 61 of the studs can be raised through the apertures in the table.

The bender mechanism, as illustrated 120 herein, is supported upon the table so that it also will be removed with the removal of the table. In the preferred embodiment of the invention illustrated the bender is in the form of a long arm or bar 64 having a 125 relatively narrow rearward extension 65 130

terminating in a rounded end 66 to engage the goods. When in normal position this rounded work engaging end is positioned to co-operate with the guide 41 upon the presser foot and preferably is positioned between the arms 42 and 43 of said guide. The bender arm or bar is supported by suitable means located at a remote distance from the line of stitching so that the bender may 10 enter within the fold of the superimposed layer and press the edge of the layer into the path of the needle.

Any suitable means may be provided for yieldingly holding the bender in operative 15 position and preferably means are provided to enable the bender to be moved bodily from operative position to facilitate the insertion and removal of the work. In the preferred construction the bender arm or 20 bar 64 is slidably mounted in ways 67 upon a shelf 68 which is pivotally supported upon a bracket extending laterally from the extension 48 of the stand. As illustrated the outer end of the shelf 68 is provided with 25 a downwardly extending standard 69 which is integral with an underlying shelf 70 having a downwardly extending wall 71 forming a continuation of the standard 69 and continuing rearwardly therefrom in an arcuate curve. The upper and lower portions 30 of the rear end of the wall are provided with extensions or bosses 72 and 73 in which are mounted trunnions 74 and 75 having conical-shaped ends adapted to engage 35 complementary sockets in a vertical boss 76 of a laterally extending arm 77 of a bracket 78 which is provided with a base 79 secured to the extension 48 of the table by screws 80. The lower trunnion 74 desirably is threaded and screwed through the 40 lower boss 72 of the downwardly extending wall 71 and is provided with a head 81 by means of which it may be adjusted. A lock nut 82 upon the screw threaded trunnion 74, 45 located intermediate of the head 81 and the boss 72, serves to lock the trunnion in adjusted position.

A strong helical spring 83, connected at 50 one end to the arm 77 of the bracket 78 and at its other end to a downwardly extending flange upon the lower shelf 70, serves normally to rock the bender supporting stand about its pivotal support in such a manner as to place the bender in operative position 55 relatively to the stitching point, and the rotary movement of the bender supporting stand is adjustably limited by a set screw 84 seated in an extension of the arm 77 of the bracket 78.

60 Any suitable means may be provided for removing the bender from operative position to permit insertion and removal of the work. Inasmuch as such movement of the bender desirably is effected simultaneously 65 with the depression of the work support,

means are provided by which the depression of the work support will also cause the removal of the bender. In the construction illustrated, a lever 85 is pivotally mounted at its lower end upon a screw or stud 86 seated in a boss extending downwardly from the bracket 78 and is provided with a cam slot 87 which receives a stud 88 extending laterally from the tubular standard 10 of the work support. The upper end of the lever 85 extends rearwardly and is bifurcated to receive a link 89 which is pivotally secured to it by a pin 90. The opposite end of the link 89 extends through a slot in the end of an extension 91 of the lower shelf 70 and is pivotally connected to such extension by a pin 92. The cam slot 87, (which is more clearly illustrated in Fig. 4), is of such form that when the tubular standard 10 of the work support is depressed the lever 85 will be swung forwardly about its pivot thereby acting through the link 89 upon the rearward extension 91 of the shelf 70 of the bender supporting stand to swing the bender stand about the axis of the trunnions 74 and 75 and remove the bender well away from operative position as illustrated in dotted lines in Fig. 6.

Means desirably are provided to permit the bender to yield readily and thus accommodate itself to different thicknesses of material or to the passage of seams. In the preferred construction illustrated the arm 64 of the bender is provided with a slot 93 the parallel side walls of which embrace a boss 94 extending upwardly from the shelf 68 and a cover plate 95 serves to retain the bender arm or bar 64 slidably within the guideways 69. An adjusting screw having a milled head 96 is mounted in the outer end of the bender and the end of the adjusting screw bears against a leaf spring 97 which is mounted in a vertical slot in the outside of the standard 69 and secured therein by a screw 98 located at a distance from the upper end of the spring. The leaf spring 97 is much weaker than the spring 83 which controls the position of the stand so that the bender yields readily to different thicknesses or seams in the material which is being sewed.

In the operation of the machine for blind stitching a superimposed layer upon a base layer, such, for example as required in sewing the facing to the body of a coat at a distance remote from the edge of the coat the base layer or body of the coat is so presented to the stitch forming mechanism that the edge of the coat extends the required distance into the recess between the upper shelf 68 which supports the bender and the lower shelf 70 of the bender supporting stand. The superimposed layer is folded around the end of the bender and lies above the bender supporting shelf 68. Thus the bender is lo-

cated between the layers of the fold of the superimposed layer and engages the superimposed layer within the angle of the fold so that the edge of the fold is pressed by the bender into the path of the needle. Desirably the end of the bender is provided with a slight groove which partially embraces the needle. Thus a proper penetration of the needle into the superimposed layer is insured.

While the bender desirably co-operates with the guide upon the presser foot above described it will be obvious that the same action may be obtained by properly adjusting the bender without the necessity of the guide although in such case very skillful manipulation of the superimposed layer will be required to retain the folded edge of the superimposed layer tightly against the bender.

This bender mechanism may also be employed for the purpose of making plaits in a single piece of fabric by folding the goods to present the desired width of the plait with the edge of the fold extending into the recess under the bender supporting shelf, the goods then being folded again over the bender so that the bender engages within the angle of the upper fold. The upper fold may then be stitched to the lower layer by a seam of blind stitches, the under fold forming the plait. This plait may be made of any desired width so that the goods may be plain plaited, or if desired the plaits thus formed flattened out and pressed to form the box plaits.

Where it is desired to sew an up-turned or folded edge of a superimposed layer upon a base layer the up-turned edge may be directed against the guides 38 and 40 of the presser foot and the bender in such case will act upon the outside of the up-turned folded edge to force the under face thereof into the path of the needle. Thus a seam of blind stitching may be made to secure the edge of the superimposed layer to the base layer in the manner usually performed by the machines of the "Arbette" type to which reference is above made.

Another feature of the invention consists in providing a bridge for supporting the goods as it passes from the work supporting table to the work support which co-operates with the presser foot. In the present work supporting table construction the top of the table is cut away to provide a recess partially to surround the work support of the sewing machine and an L-shaped plate 100 is secured to the top of the table along the side and in front of the work support to provide a smooth surface upon which the goods may be manipulated. A bridge 101 is pivotally connected at its ends to the work support and to the lateral portion 102 of the plate which is directly in front of the work

support, thus providing an inclined way leading from the work supporting table to the work clamping face of the work support.

Any suitable means may be provided for thus pivotally connecting the bridge to the work support and table. In the construction illustrated the laterally extending portion 102 of the plate is provided with a boss 103 and the adjacent end of the bridge 101 is provided with bosses 104 upon opposite sides of the boss 103 forming complementary parts of a hinge which are connected by a pintle 105. The bridge 101 has at its opposite end an upwardly curved lip 106 which underlies the forward end of the work support and is clamped thereagainst by a leaf spring 107 which is secured to the under face of the work support by a screw 108. The under face of the work support desirably is provided with a recess 109 to receive the end of the lip 106 and to permit a sliding and pivotal movement between the lip and the work support when the work support is depressed.

In order to assist the operator in controlling the feed of the goods to the work the bridge 101 is provided with a hump 110 located directly in front of the stitching point. This causes the base layer to bend upwardly in advance of the stitching point and facilitates the guiding of the goods to the needle. It also imposes a slight tension upon the goods which insures uniformity of stitching. In order to enable the operator to increase the tension upon the base layer the humped portion of the bridge is provided with a preferably flat inclined and roughened surface 111 which extends from about midway of the hump to the side edge of the bridge. By reason of this construction the manipulation of the goods by the operator is greatly facilitated.

It will be understood that the embodiment of the invention disclosed herein is of an illustrative character and is not restrictive and that various changes in form, construction and arrangement of parts may be made within the spirit and scope of the following claims.

Having thus described the invention, what is claimed as new, and desired to be secured by Letters Patent, is:

1. A blind stitch sewing machine for felling a superimposed layer of material upon a base layer comprising a bed plate, a reciprocating needle moving in the general direction of the line of stitching and complementary stitch forming mechanism, a guide for directing a turned-up edge of the superimposed layer in the direction of the line of stitching adjacent to the path of the needle and a bender supported upon said bed plate acting continuously to force the turned-up portion of the superimposed layer into the path of the needle at the stitching

point and means acting to present the base layer in the path of the needle at predetermined intervals.

2. A blind stitch sewing machine for fell-
5 ing a superimposed layer of material upon a base layer comprising a bed plate, a curved oscillating needle and complemental stitch forming mechanism located and operating above said bed plate, a guide for directing a turned-up edge of the superimposed layer in the direction of the line of stitching adjacent to the path of the needle and a yieldable bender supported upon said bed plate acting in a direction substantially parallel
10 to said bed plate and normal to the line of stitching to force the turned-up edge of the superimposed layer into the path of the needle at the stitching point and means acting to present the base layer in the path
15 of the needle at predetermined intervals.

3. A blind stitch sewing machine for fell-
ing a superimposed layer of material upon a base layer comprising a bed plate, a curved oscillating needle and complemental stitch
25 forming mechanism located and operating above said bed plate, a guide for directing a turned-up edge of the superimposed layer in the direction of the line of stitching adjacent to the path of the needle, a bender supported upon said bed plate acting continuously to force the turned-up portion of the superimposed layer into the path of the needle at the stitching point, means for removing said bender from operative position
30 to facilitate the introduction of the work and means acting to present the base layer in the path of the needle at predetermined intervals.

4. A blind stitch sewing machine for fell-
40 ing a superimposed layer of material upon a base layer comprising a bed plate, a curved oscillating needle and complemental stitch forming mechanism located and operating above said bed plate, a guide for directing a turned-up edge of the superimposed layer in the direction of the line of stitching adjacent to the path of the needle, a yieldable bender supported upon said bed plate acting in a direction substantially parallel to said
45 bed plate and normal to the line of stitching to force the turned-up edge of the superimposed layer into the path of the needle at the stitching point and means for swinging said bender bodily from operative position to facilitate the introduction of the work and
50 means acting to present the base layer in the path of the needle at predetermined intervals.

5. A blind stitch sewing machine for fell-
60 ing a superimposed layer of material upon a base layer comprising a bed plate, a curved oscillating needle and complemental stitch forming mechanism located and operating above said bed plate, a guide for directing a turned-up edge of the superimposed layer

in the direction of the line of stitching adjacent to the path of the needle, a bender support pivotally mounted at a distance remote from the line of stitching to permit the work to extend well beyond the line of stitching
70 and a bender yieldably mounted on said support having a work engaging end positioned to force the turned-up portion of the superimposed layer into the path of the needle at the stitching point and means acting to present the base layer in the path of the needle at predetermined intervals.
75

6. A blind stitch sewing machine for fell-
ing a superimposed layer of material upon a base layer comprising a bed plate, an os-
cillating and laterally vibrating needle and complemental stitch forming mechanism located and operating above said bed plate, a guide for directing a turned-up edge of the superimposed layer in the direction of the
80 line of stitching adjacent to one of the paths of the needle, a pivotally mounted bender support located at a distance remote from the line of stitching to permit the work to extend well beyond the line of stitching and a bender yieldably mounted upon said work support having a work engaging end positioned to force the turned-up portion of the superimposed layer into the path of the needle at the stitching point and means for
85 swinging said bender support about its pivot to remove the bender from operative position and thereby facilitate the introduction of the work and means acting to present the base layer in the other path of the needle
90 at predetermined intervals.
95

7. A blind stitch sewing machine for fell-
ing a superimposed layer of material upon a base layer comprising a curved oscillating and laterally vibrating needle and complemental stitch forming mechanism located and operating above said work support, a presser foot having a guide for directing a turned-up edge of the superimposed layer in the direction of the line of stitching adjacent to one of the paths of the needle and a yieldable bender supported upon the bed plate co-operating with said guide and acting continuously to force said turned-up portion of the superimposed layer into the path of the needle at the stitching point and means acting to present the base layer in the other path of said needle at predetermined intervals.
100
110
115

8. A blind stitch sewing machine for fell-
ing a superimposed layer upon a base layer of material comprising a bed plate, an over-
hanging arm having a head carrying a curved oscillating needle, complemental
120 stitch forming mechanism and feeding mechanism, a presser foot rigidly supported upon said head and having a guide for directing the turned-up edge portion of the superimposed layer in the direction of the line of stitching adjacent to the path of the
125
130

- needle, a yieldable work support extending above the plane of the bed plate and co-operating with said presser foot to clamp the work therebetween, a yieldable bender supported upon said bed plate acting to force the turned-up portion of the superimposed layer into the path of the needle at the stitching point, means for depressing the work support out of work clamping relation to the presser foot and simultaneously operable means for removing the bender from operative position to facilitate the insertion and removal of the work. 9. A blind stitch sewing machine for fell-
ing a superimposed layer upon a base layer of material comprising a bed plate, an overhanging arm having a head carrying a curved oscillating needle, complemental stitch forming mechanism and feeding mechanism, a presser foot rigidly supported upon said head and having a guide for directing the turned-up edge portion of the superimposed layer in the direction of the line of stitching adjacent to the path of the needle, a yieldable work support extending above the plane of the bed plate and co-operating with said presser foot to clamp the work therebetween, a work supporting table detachably mounted upon said bed plate having a work supporting surface positioned to co-operate with said work support, a bender support pivotally mounted upon said table and having a bender presenting a work engaging end positioned to engage the turned-up portion of the superimposed layer and resilient means acting upon said bender support to hold the bender normally in work engaging position.
10. A blind stitch sewing machine for fell-
ing a superimposed layer upon a base layer of material comprising a bed plate, an overhanging arm having a head carrying a curved oscillating needle, complemental stitch forming mechanism and feeding mechanism, a presser foot rigidly supported upon said head and having a guide for directing the turned-up edge portion of the superimposed layer in the direction of the line of stitching adjacent to the path of the needle, a yieldable work support extending above the plane of the bed plate and co-operating with said presser foot to clamp the work therebetween, a work supporting table detachably mounted upon said bed plate having a work supporting surface positioned to co-operate with said work support, means for depressing the work support away from work clamping relation to said presser foot, a stud on said work support and means including a lever pivotally mounted on said table and connected to said bender support and having a cam slot engaging said stud operable to swing the bender support about its pivot away from and into operative position in synchronism with like movements of the work support when moved away from and into work clamping relation.
11. A blind stitch sewing machine for fell-
ing a superimposed layer upon a base layer of material comprising a bed plate, an overhanging arm having a head carrying a curved oscillating needle, complemental stitch forming mechanism and feeding mechanism, a presser foot rigidly supported upon said head and having a guide for directing the turned-up edge portion of the superimposed layer in the direction of the line of stitching adjacent to the path of the needle, a yieldable work support extending above the plane of the bed plate and co-operating with said presser foot to clamp the work therebetween, a work supporting table detachably mounted upon said bed plate having a work supporting surface positioned to co-operate with said work support, a bender supporting stand pivotally mounted upon said table and presenting a recess to permit the work to extend well beyond the position of the line of stitching, means for holding the stand normally in operative position, a bender slidably mounted upon said stand having an end portion to engage the turned-up portion of the superimposed layer at the stitching point and resilient means acting upon said bender to hold it in work engaging position.
12. A blind stitch sewing machine for fell-
ing a superimposed layer upon a base layer of material comprising a bed plate, an overhanging arm having a head carrying a curved oscillating needle, complemental stitch forming mechanism and feeding mechanism, a presser foot rigidly supported upon said head and having a guide for directing the turned-up edge portion of the superimposed layer in the direction of the line of stitching adjacent to the path of the needle, a yieldable work support extending above the plane of the bed plate and co-operating with said presser foot to clamp the work therebetween, a work supporting table detachably mounted upon said bed plate having a work supporting surface positioned to co-operate with said work support, a bender supporting stand pivotally mounted upon said table and presenting a recess to permit the work to extend well beyond the position of the line of stitching, means for holding the stand normally in operative position, a bender slidably mounted upon said stand having an end portion to engage the turned-up portion of the superimposed layer at the stitching point and resilient means acting upon said bender to hold it in work engaging position.
13. A blind stitch sewing machine for

5 felling a superimposed layer upon a base layer of material comprising a bed plate, an overhanging arm having a head carrying a curved oscillating needle, complementary
10 stitch forming mechanism and feeding mechanism, a presser foot rigidly supported upon said head and having a guide for directing the turned-up edge portion of the superimposed layer in the direction of the line of stitching adjacent to the path of the
15 needle, a yieldable work support extending above the plane of the bed plate and co-operating with said presser foot to clamp the work therebetween, a work supporting
20 table detachably mounted upon said bed plate having a work supporting surface to co-operate with said work support, a bender supporting stand pivotally mounted upon
25 said table and presenting a recess to permit the work to extend well beyond the position of the line of stitching, means for holding the stand normally in operative position, a bender slidably mounted upon said stand having an end portion to engage the turned-up portion of the superimposed layer at the stitching point, resilient means acting upon
30 said bender to hold it in work engaging position and means intermediate of said bender and resilient means for adjusting the force with which the bender engages the superimposed layer.

14. A blind stitch sewing machine for felling, upon a base layer, a superimposed layer of material which is folded to present an edge, comprising a bed plate, a curved needle oscillating in the general direction of the line of stitching and complementary stitch forming mechanism located and operating above said bed plate, and means interposed between the layers of said fold engaging the superimposed layer within the angle of the fold and acting to present the edge of said superimposed layer in the path of the needle.

15. A blind stitch sewing machine for felling, upon a base layer, a superimposed layer of material which is folded to present an edge, comprising a bed plate, a curved needle oscillating in the general direction of the line of stitching and complementary stitch forming mechanism located and operating above said bed plate, a slidably mounted yieldable bender interposed between the layers of said fold engaging the superimposed layer within the angle of the fold and acting continuously to present the edge of the superimposed layer in the path of the needle.

16. A blind stitch sewing machine for felling, upon a base layer, a superimposed layer of material which is folded to present an edge comprising a bed plate, a curved needle oscillating in the general direction of the line of stitching and complementary stitch forming mechanism located and oper-

ating above said bed plate, a slidably mounted yieldable bender interposed between the layers of said fold engaging the superimposed layer within the angle of the fold and acting continuously to present the edge of the superimposed layer in the path of the needle and means for bodily swinging the bender from operative position to facilitate the introduction and removal of the work. 75

17. A blind stitch sewing machine for felling, upon a base layer, a superimposed layer of material which is folded to present an edge, comprising a bed plate, an overhanging arm having a head carrying a curved oscillating needle and complementary stitch forming mechanism, feeding mechanism and a presser foot provided with a guide for directing the folded edge of the superimposed layer in the direction of the line of stitching and adjacent to the path of the needle, a yieldable work support extending above the bed plate and co-operating with the presser foot to clamp the work therebetween, a work supporting table detachably mounted upon said bed plate having a laterally extending bracket, a stand pivotally mounted on said bracket having a standard remote from the line of stitching and an overhanging shelf lying substantially in the normal plane of the work support, a bender mounted upon said shelf, resilient means acting upon said stand to swing said bender into co-operative relation with said edge guide at the stitching point and thereby to force the folded edge of the superimposed layer into the path of the needle. 80 85 90 95 100

18. A blind stitch sewing machine for felling, upon a base layer, a superimposed layer of material which is folded to present an edge, comprising a bed plate, an overhanging arm having a head carrying a curved oscillating needle and complementary stitch forming mechanism, feeding mechanism and a presser foot provided with a guide for directing the folded edge of the superimposed layer in the direction of the line of stitching and adjacent to the path of the needle, a yieldable work support extending above the bed plate and co-operating with the presser foot to clamp the work therebetween, a work supporting table detachably mounted on said bed plate having a laterally extending bracket, a stand pivotally mounted on said bracket having a standard remote from the line of stitching, an overhanging shelf lying substantially in the normal plane of the work support, a bender yieldably mounted on said shelf, resilient means acting upon said stand to swing said bender into co-operative relation with said edge guide at the line of stitching and adjustable means for limiting the swinging movement of the stand. 105 110 115 120 125 130 135

19. A blind stitch sewing machine for felling, upon a base layer, a superimposed layer of material which is folded to present an edge comprising a bed plate, an overhanging arm having a head carrying a curved oscillating needle and complemental stitch forming mechanism, feeding mechanism and means for presenting the base and superimposed layers respectively in the path of the needle, a work supporting table mounted upon said bed plate having a work supporting surface located below the normal plane of the work support and a bridge located in front of the work support pivotally connected at its ends respectively to the work support and to the table. 70
- 10 superimposed layer in the direction of the line of stitching and adjacent to the path of the needle, a yieldable work support extending above the bed plate and co-operating with the presser foot to clamp the work 75
- 15 therebetween, a work supporting table detachably mounted on said bed plate having a laterally extending bracket, a stand pivotally mounted on said bracket having a standard remote from the line of stitching, 80
- 20 an overhanging shelf lying substantially in the normal plane of the work support, a bender slidably mounted upon said shelf, a spring acting upon said stand to swing said bender into co-operative relation with said 85
- 25 edge guide, adjustable means for limiting the swinging movement of said stand and a spring, relatively lighter than the stand-actuating spring, engaging said sliding bender and acting to press the end thereof 90
- 30 into engagement with the fold of the superimposed layer. 95
20. A blind stitch sewing machine for felling, upon a base layer, a superimposed layer of material which is folded to present an edge comprising a bed plate, an overhanging arm having a head carrying a curved oscillating needle and complemental stitch forming mechanism, feeding mechanism and a presser foot provided with a guide for 100
- 35 directing the folded edge of the superimposed layer in the direction of the line of stitching and adjacent to the path of the needle, a yieldable work support extending above the bed plate and co-operating with the presser foot to clamp the work therebetween, a work supporting table detachably mounted on said bed plate having a laterally extending bracket, a stand pivotally mounted on said bracket having a standard re- 105
- 40 mote from the line of stitching, an overhanging shelf lying substantially in the normal plane of the work support, a bender slidably mounted upon said shelf, a spring acting upon said stand to swing said bender into co-operative relation with said edge 110
- 45 guide, adjustable means for limiting the swinging movement of said stand and a spring, relatively lighter than the stand-actuating spring, engaging said sliding bender and acting to press the end thereof into engagement with the fold of the superimposed layer and adjusting means interposed between said bender and its spring. 115
- 50 21. A blind stitch sewing machine for felling, upon a base layer, a superimposed 120
- 55 layer of material which is folded to present an edge comprising a bed plate, an overhanging arm having a head carrying a curved oscillating needle and complemental stitch forming mechanism, feeding mechanism and means for presenting the base and superimposed layers respectively in the path of the needle, a work supporting table mounted upon said bed plate having a work supporting surface located below the normal plane of the work support and a bridge located in front of the work support pivotally connected at its ends respectively to the work support and to the table. 125
22. A blind stitch sewing machine for felling, upon a base layer, a superimposed layer of material which is folded to present an edge comprising a bed plate, an overhanging arm having a head carrying a curved oscillating needle and complemental stitch forming mechanism, feeding mechanism and means for presenting the base and superimposed layers respectively in the path of the needle, a work supporting table mounted upon said bed plate having a work supporting surface located below the normal plane of the work support and a bridge having a humped upper surface located in front of the work support and pivotally connected at its ends respectively to the work support and to the table. 130
23. A blind stitch sewing machine for felling, upon a base layer, a superimposed layer of material which is folded to present an edge comprising a bed plate, an overhanging arm having a head carrying a curved oscillating needle and complemental stitch forming mechanism, feeding mechanism and means for presenting the base and superimposed layers respectively in the path of the needle, a work supporting table mounted upon said bed plate having a work supporting surface located below the normal plane of the work support and a bridge having an upper surface presenting a hump with a roughened laterally inclined surface extending from the central portion thereof downwardly beneath the path of the base layer to permit the operator, by pressing the base layer upon said roughened portion, to retard the feed of said base layer. 135
24. A blind stitch sewing machine for felling, upon a base layer, a superimposed layer of material which is folded to present an edge, comprising a bed plate, an overhanging arm having a head carrying a curved oscillating needle and complemental stitch forming mechanism and feeding mechanism and a presser foot provided with a guide for directing the folded edge of the superimposed layer in the direction of the line of stitching and adjacent to the path of the needle, means for presenting the base and superimposed layers respectively in the path of the needle, a work supporting table 140

detachably mounted upon said bed plate having a work supporting surface located below the normal plane of the work support and a bridge hinged at one end to the table 5 and pivotally and detachably connected at its other end to the work support.

25. A blind stitch sewing machine for felling, upon a base layer, a superimposed layer of material which is folded to present an 10 edge, comprising a bed plate, an overhanging arm having a head carrying a curved oscillating needle and complementary stitch forming mechanism and feeding mechanism and a presser foot provided with a guide 15 for directing the folded edge of the superimposed layer in the direction of the line of

stitching and adjacent to the path of the needle, means for presenting the base and superimposed layers respectively in the path of the needle, a work supporting table detachably mounted upon said bed plate having a work supporting surface located below the normal plane of the work support, a bridge hinged at one end to the table and provided at its other end with a lip underlying 20 the front end of the work support and a spring clamp for holding said lip in engagement with the under side of the work support. 25

In testimony whereof, I have signed my name to this specification.

HARLEY C. MOULTON.
